UNITED STATES PATENT OFFICE.

PETER WHITE, OF ST. LOUIS, MISSOURI.

HYDRANT.

SPECIFICATION forming part of Letters Patent No. 394,529, dated December 11, 1888.

Application filed April 23, 1888. Serial No. 271,563. (No model.)

To all whom it may concern:

Be it known that I, PETER WHITE, of the city of St. Louis, in the State of Missouri, have invented a certain new and useful Improvement in Hydrants, of which the following is a full, clear, and exact description, reference being had to the accompanying drawings, forming part of this specification, and in which—

10 Figure I is a vertical section illustrative of my invention. Fig. II is a side elevation. Fig. III is a detail front elevation, part in section on line III III, Fig. II. Fig. IV is a top view. Fig. V is a transverse section taken 15 on line V V, Fig. I. Fig. VI is a detail section of the lower end of the outer cylinder or tube, showing the inner pipe or tube in side view, and showing the valve closed. Fig. VII is a detail section through the outer cylinder 20 or tube, and also through the inner pipe, showing the valve open. Fig. VIII is a transverse section on line VIII VIII, Fig. VI. Fig. IX is a detail view illustrating the device for use as a street washer or sprinkler.

25 My invention relates to certain improvements in hydrants; and it consists in features of novelty hereinafter fully described, and pointed out in the claims.

Referring to the drawings, 1 represents an 30 outer cylinder or tube inclosed at its upper portion in a housing or casing, 2.

3 represents the water-pipe, which is located within the outer tube, 1, and which extends from the bottom to near the top of the tube. 35 The top of this pipe screws into a plug or block, 4, which is cast with an opening, 5. On the block 4 is also cast a spout, 6, and a projection or face, 7. (See Fig. V.) The upper end of the block is reduced to form a stem 40 portion, 8, that extends through a cap, 9, and to which the operating-lever 100 is pivoted at 10. On the cap is an arm, 11, to which the lever is pivoted at 12. The upper end, 13, of the housing or casing is provided with a 45 straight vertical slot, 14, to receive the spout 6. This slot is closed above the spout by means of a tongue or extension, 15, formed upon or secured to the cap 9, (see Figs. I and III,) whose width is equal to that of the slot 50 14, so that it may fit within the latter flush with the housing, as shown.

In putting the parts together the block 4, with the spout 6 and pipe 3, would be inserted. Then the cap 9 would be put in place and the lever 100 attached. The cap is held 55 in the part 13 of the housing by any suitable means. I have shown it held in place by means of screws 16, (see Fig. IV,) that pass through the cap and enter nuts 17, held between lugs 18 on the housing. (See Figs. II 60 and III.)

The slot 14 is made somewhat longer than the diameter of the spout 6, as shown in Figs. I and III, to allow the spout to move up and down with the pipe 3 in opening and closing 65 the hydrant-valve, and the escape of water (that may get between the pipe 3 and the part 13 of the housing, or between the pipe 3 and the outer tube or cylinder 1) is prevented by means of the lip or enlargement 7, formed 70 upon the block 4. This enlargement is formed to the contour of the inner surface of the housing, so as to close the slot, as shown in Figs. I and V.

The cap 9 is formed with an apex, 50, from 75 where it is curved outwardly and downwardly, as shown at 51. The body of the lever is formed in the shape of a hood, 52, and the object of thus constructing the hood and the cap is, that the water escaping through the cap 80 around the stem 8 will be deflected downwardly by the hood 52 of the lever onto the incline 51 of the cap, and will run off the periphery of the cap onto the ground, and will not enter between the housing and cylinder 85 to rust the parts.

The valve, which is composed of a short piece of tube, 18, and rings 19, is secured to the lower end of the pipe 3. (See Figs. VI and VII.)

90 20 represents the inlet-neck, to which the pipe from the main is connected. The water passes (when the valve is opened) through this neck and up through the pipe 3, as indicated by arrows in Fig. VII, and when the 95 valve is closed, as shown in Fig. VI, this passage of the water is prevented and the hydrant is thus closed.

To allow the water to drain from the pipe 3 when the hydrant is closed, the tube 18 is provided with perforations 21, which, when the 100 valve is closed, coincide with or come opposite

to an opening, 22, in the lower part of this cylinder 1. One of the packing-rings 19 is located above and one below these perforations 21. The tube 18 is grooved circumferentially 5 to receive the rings 19.

To allow the escape of water that may get between the pipe 3 and cylinder 1, I form a perforation, 23, in the latter above the tube 18, (see Figs. VI and VII,) through which such 10 water may escape. This valve part of my invention may be applied to a street sprinkler or washer, as shown in Fig. IX, where the cap (which would be in line with the pavement) is provided with a cup, 24, having a lid or 15 cover, 25, pivoted to it, and the upper end of the pipe 3 is provided with wings, one of which has a notch, 26, to receive a button, 27, pivoted to the cap at 28. When the hydrant is 20 opened, this button is turned into the notch 26, and the valve is thus held open. The upper end of the pipe 3 is provided with a neck, 29, for the attachment of a hose. The hood 52 also serves to protect the stem 8 and cap 9 from snow and sleet in winter.

25 The portion of the tube 18 between the top and second rings 19 is grooved to form an annular chamber, 60, opposite the perforations 21, and which delivers the water to the escape 22 from all around the tube.

30 I claim as my invention—

1. In a hydrant, the combination, with the water-pipe and a block on the end of said pipe provided with a spout, of a housing having a slot to receive the spout, a cap on the housing, and a downwardly-projecting tongue on 35 said cap, whose width is equal to that of the slot, and which is adapted to fit within and close the upper portion of said slot, and the said block resting against the inner surfaces of said tongue and housing, whereby the slot 40 is always closed, as set forth.

2. In a hydrant, the combination, with the housing and a vertically-movable pipe located within said housing, of the upper end, 13, of said housing, having the vertical slot 14, a 45 plug or block, 4, on the upper end of said pipe, the stem 8, formed integrally with said block, the face or projection 7 on said block or plug resting against the inner surface of said housing and closing the lower end of said slot, and 50 adapted to be moved vertically by said pipe, the cap 9, having a perforation for said stem, and a downwardly-projecting tongue on said cap fitting in and closing the upper end of said slot and resting against said face 7, substantially as set forth.

PETER WHITE.

In presence of—

GEO. H. KNIGHT,
JOS. WAHLE.
